CAR CONSTRUCTION

George T. Johnson, Columbus, Ohio, assignor to
The Buckeye Steel Castings Company, Colum-
bus, Ohio

Application November 9, 1931, Serial No. 573,966

8 Claims. (Cl. 213—57)

This invention relates to improvements in center castings and body bolsters for railway freight cars, and more especially to a device of this character designed for use with draft mechanism of the tandem draft gear type.

If draft mechanism is used in which the draft gearings are arranged in tandem formation, this prevents the back stop used with draft mechanism from projecting forwardly to the same extent as in the past, due to the fact that some of the space previously occupied by the back stop must be utilized to accommodate the rear draft gearing.

The primary purpose of the present invention is to provide a combined center casting and body bolster construction having the necessary pocket or clearance space to accommodate the rear draft gearing, and yet of such design as to not impair the strength of the body bolster construction.

With the foregoing object outlined and with other objects in view which will appear as the description proceeds, the invention consists in the novel features hereinafter described in detail, illustrated in the accompanying drawings, and more particularly pointed out in the appended claims.

In the drawings,

Fig. 1 is a plan view of the improved construction, the portion at the left being taken from the bottom, and the portion at the right being taken from the top and having the built-up construction omitted.

Fig. 2 is a front elevation of the same, partly in transverse vertical section, the section being taken on the line 2—2 of Fig. 1.

Fig. 3 is a vertical sectional view of the same, taken lengthwise of the car.

Figs. 4, 5 and 6 are views like Figs. 1, 2 and 3 respectively, but showing a modification. The sectional portion Fig. 5 is taken on the line 5—5 of Fig. 4.

Fig. 7 is a top plan view partly in horizontal section of another modification.

Fig. 8 is a longitudinal vertical sectional view of the same.

Fig. 9 is a sectional view of a detail taken on line 9—9 of Fig. 7.

Referring first to the embodiment of the invention illustrated in Figs. 1 to 3 inclusive, it will be noted that the center casting 22 is integral with the center plate 23 which has the usual king pin aperture 23a.

A web 24 which forms the main portions of the bottom of a body bolster, is made up of flanges 55 or arms which project laterally from the center

plate, and in these arms, the side bearings 25 are arranged directly below side bearing braces 26; all of the parts 22, 23, 24, 25 and 26 being portions of a one-piece metal structure, or being integral with one another. Each side bearing is preferably formed by placing a pocket 25a in the casting and bracing the same by the brace 26 which includes a transverse web 26a reinforced at opposite sides by centrally disposed ribs 26b.

The center casting has the usual bearing plate 29 arranged directly at the rear of the pocket 29a which accommodates the rear draft gearing (not shown), and in accordance with the present invention, the bearing plate 29 extends entirely 15 across the central portion of the casting and is arranged rearwardly of the axis of the king pin hole 23a.

Extending rearwardly from the plate 29 are a pair of side plates 30 which are provided with 20 holes to receive the rivets 31 employed in securing the casting to the center sills 35.

In my new design, the inner flanges 34 of the center sills are cut away at 33 to accommodate the bottom tie 32 of the casting, and it will be noted 25 that this bottom tie has a rearwardly extending overhanging ledge 32a which overlaps the cut-away portions of the flanges 34. A rib 32b is vertically arranged at the central portion of the casting and extends from the tie 32 to the bearing plate 29 for reinforcing purposes. Horizontal ribs 32c also extend from the wall 29 to the side walls 30 for reinforcing purposes.

Immediately forward of the wall 29 the center plate 23 is braced by a vertical rib 36, and a 35 transverse flange 37.

Only the bottom, side bearings, their braces and the central portion of the body bolster 28 are formed of the one-piece metal casting, and the remainder of the body bolster is preferably made 40 of built-up metal parts, which are spliced to the casting by the usual pressed plate construction 38.

The construction illustrated in Figs. 4 to 6 inclusive differs from that shown in Figs. 1, 2 and 3 45 in that the center casting 22x is made separate from the portion which forms the cross part of the bolster, so that the inturned flanges 34x of the center sills 35x may extend forward beyond the axis of the king pin hole as indicated at 31x 50 in Fig. 4. It will be noted that the center casting has an integral plate 32x which, however, is not cast with the center plate 23x. In this case, the rib 36x and flange 37x, as well as the reinforcing ribs at the rear of the plate 29x are 55

cast integral with the center casting 22x. The general details of the center plate 23x, arms 24x, side bearings 25x and said bearing braces 26x, all of which are cast integral, are the same as the 5 construction illustrated in Figs. 1 to 3 inclusive.

The embodiment illustrated in Figs. 7 to 9 inclusive differs from that shown in Figs. 1 to 3 inclusive in that the flanges or arms 24x are relatively short and terminate just beyond the center 10 sills 35e. They are spliced to the usual pressed plate construction 38e between the center plate 23e and the side bearings (not shown). Of course, in this instance, the side bearings and their braces would be separate castings.

15 It is apparent that the invention may be modified for accomplishing the same result, without departing from the spirit of the invention, as expressed in the claims.

What is claimed and desired to be secured by 20 Letters Patent is:

1. In a car construction, a body bolster including a center casting having a center bearing plate provided with a king pin aperture, the center casting and plate forming a draft gear receiving pocket positioned above the plate, and oppositely extending arms integral with said plate and forming portions of the bottom of said bolster, the center casting having a vertical bearing wall and a tie plate, both arranged rearwardly of said aperture and being integral with one another, the rear end of the tie plate being provided with an overhanging ledge adapted to overlap portions of the inner flanges of the car center sills.

30 2. In a car construction, spaced apart center sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, and a vertical bearing wall of substantially the same height as the center sills, said bearing wall being integral with the front ends of the side walls and rigidly united at its lower portion with said center plate, the bearing wall being positioned closer to the king pin aperture than to the front edge of the center plate whereby a 35 pocket is provided in the central portion of the bolster to accommodate the rear end of tandem draft gearing.

35 3. In a car construction, spaced apart center sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, a vertical bearing wall of substantially the same height as the center sills, said bearing wall being integral with the front ends of the side walls and rigidly united at its lower portion with said center plate, the bearing wall being positioned closer to the king pin aperture than to the front edge of the center plate whereby a pocket is provided in the central portion of the bolster to accommodate the rear end of tandem draft gearing, and horizontal ribs integrally connecting the rear surface of the bearing wall to the inner surfaces of the side walls.

70 4. In a car construction, spaced apart center

sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, a vertical bearing wall of substantially the same height as the center sills, said bearing wall being integral with the front ends of the side walls and rigidly united at its lower portion with said center plate, the bearing wall being positioned closer to the king pin aperture than to the front edge of the center plate whereby a pocket is 15 provided in the central portion of the bolster to accommodate the rear end of tandem draft gearing, and a vertical rib integrally united with the rear portion of the bearing wall and rigidly united with the upper surface of the center plate. 20

5. In a car construction, spaced apart center sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, and a vertical bearing wall of substantially the same height as the center sills, said bearing wall being integral with the front ends of the side walls and rigidly united at its lower portion with said center plate, the bearing wall being positioned closer to the king pin aperture than to the front edge of the center plate whereby a pocket is provided in the central portion of the bolster to accommodate the rear end of tandem draft gearing, said flanges being of less length than the portions of the bolster which are arranged at opposite sides of the center sills. 35

6. In a car construction, spaced apart center sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, and a vertical bearing wall of substantially the same height as the center sills, said bearing wall being integral with the front ends of the side walls and rigidly united at its lower portion with said center plate, the bearing wall being positioned closer to the king pin aperture than to the front edge of the center plate whereby a pocket is provided in the central portion of the bolster to accommodate the rear end of tandem draft gearing, said center sills having inwardly extending lower flanges terminating in the vicinity of said center plate. 55

7. In a car construction, spaced apart center sills, a body bolster, a center casting for the body bolster designed to accommodate tandem draft gearing and having a center plate provided with oppositely projecting flanges forming a portion of the bottom of said bolster, said center plate having a king pin aperture, parallel side walls for the casting rigidly united with the center plate and rigidly connected to the center sills, and a vertical bearing wall of substantially the same height as the center sills, said bearing wall being integral with the front ends of the side walls and rigidly united at its lower portion with said 70

center plate, the bearing wall being positioned closer to the king pin aperture than to the front edge of the center plate whereby a pocket is provided in the central portion of the bolster to 5 accommodate the rear end of tandem draft gearing, said center sills having inwardly extending lower flanges terminating in the vicinity of said center plate, the center plate terminating at its rear end in a ledge which overhangs the 10 ends of the last mentioned flanges and integrally connects said side walls.

8. In a car construction, a body bolster including a center casting having a center bearing

plate provided with a king pin aperture, the center casting and plate forming a draft gear receiving pocket positioned above the plate, and oppositely extending arms integral with the plate and forming portions of the bottom of said 5 bolster, the center casting having a vertical bearing wall and a tie plate, said bearing wall being positioned closer to said aperture than to the front edge of the plate and being integral with the tie plate, said center plate being recessed to 10 accommodate the inner flanges of the car center sills.

GEORGE T. JOHNSON.
